CIGARETTE SUPPLY CLIP OR RECEPTACLE

Charles E. Wester, Ironwood, Mich.

Application March 3, 1931. Serial No. 519,890

3 Claims. (Cl. 206—41)

This invention relates to improvements in article receptacles designed to facilitate the ready transferal of the contents thereof to a receiving receptacle and pertains particularly to a receptacle or clip for a plurality of cigarettes, so designed that the contents may be readily transferred to a dispenser.

The primary object of the present invention is to provide a cigarette package or clip of simple 10 design and adapted to be made of an inexpensive material such as pasteboard, in which cigarettes may be packaged by the manufacturer and from which they may be readily ejected by the finger, into the receiving receptacle of a dispenser.

Another object of the invention is to provide 15 an article of the above described character which has a discharge opening through which the cigarettes may be forced, which is normally guarded by inturned flexible flanges which prevent the 20 contents of the receptacle from escaping accidentally.

The invention will be best understood from a 25 consideration of the following detailed description taken in connection with the accompanying drawing forming a part of the present invention with the understanding, however, that the invention is not confined to any strict conformity with the showing of the drawing but may be 30 changed or modified so long as such changes or modifications mark no material departure from the salient features of the invention, as expressed in the appended claims.

In the drawing:—

Figure 1 is a view in perspective of a device 35 embodying the present invention showing the same in position in the receiving end of the magazine of a cigarette dispensing device, the structure of which forms the subject-matter of a co-pending application;

Figure 2 is a longitudinal sectional view through 40 the device;

Figure 3 is a sectional view taken on the line 3—3 of Figure 2;

Figure 4 is a view of the discharge end of the 45 device.

Referring now more particularly to the drawing 50 wherein like numerals of reference indicate corresponding parts throughout the several views, the numeral 1 indicates generally the package or article clip embodying the present invention and the numeral 2' indicates generally the dispensing device into which the contents of the clip 55 are discharged, this dispensing device forming, as previously stated, the subject-matter of a co-pending application.

The clip or receptacle 1 is preferably constructed of light cardboard and as shown, it is of flat rectangular design. The front wall 2 is provided with the relatively wide slot 3 which is continued transversely of the type edge wall 4, as 60 indicated at 5.

The back wall 6 has formed integral therewith a tab 7 which is substantially the same width as the slots 3 and 5 so that it may be folded 65 thereinto when the package is made up and wrapped for storage or shipment.

The opposite end wall from the wall 4 is entirely open and the adjacent edges of the front and back walls 2 and 6 have extended therefrom the flaps 8 and 9, respectively, while the adjacent 70 edges of the side walls 10 have formed integral therewith the flaps 11. The flaps 8, 9 and 11, as shown in Figures 2 and 4 are bent to normally extend inwardly in convergent relation across the open end of the receptacle and as shown 75 in Figure 2, they thus coat to retain in the receptacle the cigarettes 12.

In the use of the present cigarette supply clip or package in association with the dispenser 2', the discharge end of the clip is inserted into the 80 dispenser in the manner shown and the pull tab 7 straightened out, as also shown. By grasping the dispenser 2 with the left hand and placing the index finger of the left hand in the upper part of the slot 3 against the cigarettes 12, and then grasping the tab 7 with the right hand and pulling the clip away from the dispenser it will be readily seen that the contents of the clip 85 will be discharged into the dispenser in the manner illustrated. 90

I claim:—

1. A supply clip of the character described, comprising a flat receptacle having front and back walls, side edge walls and one end edge wall, the opposite end edge being opened throughout, a flap extending throughout the length of and projecting from the front and back wall at the edge of each adjacent the open edge of the receptacle, coacting flaps at the ends of the side walls adjacent the open edge of the receptacle, said front wall having a relatively narrow opening cut therein from adjacent the attached flap to and extending across the said one end edge wall, and a handling tab attached to the back wall at that end of the said opening which extends across the said one end wall, said tab being of substantially the same width as the opening to permit of its being folded over to lie therein. 95

2. A supply clip of the character described, 100 comprising a flat receptacle having front and

back walls, side edge walls and one end edge wall, the opposite end edge being open throughout, said front wall having a relatively narrow opening cut longitudinally therein from adjacent the open 5 end edge of the receptacle to and extending across the said one end edge wall, and a handling tab attached to the back wall at that end of said opening which extends across the said one end wall, said tab being of substantially the 10 same width as the opening to permit of its being folded over to lie therein flush with the adjacent walls.

3. A supply clip of the character described, comprising a flat receptacle having front and 15 back walls, side edge walls and one end edge wall, the opposite end edge being open through-

out, a flap extending throughout the length of and projecting from the front and back wall along that edge of each which borders the open edge of the receptacle, coacting flaps at the ends of the side edge walls which border the open edge of the receptacle, said side wall and front and back wall flaps being normally folded inwardly to prevent the escape of articles from the receptacle, and said front wall having a relatively narrow opening cut longitudinally therein to facilitate the forcing of the said articles from the receptacle past said flaps, the flap at the edge of the front wall extending across the front wall opening. 80 85
